UNITED STATES PATENT OFFICE.

ROBERT L. ALEXANDER, WILLIAM WISHART, AND HARRY H. WATERS, OF CLINTON, IOWA, ASSIGNORS TO CLIMAX ENGINEERING CO., OF CLINTON, IOWA, A CORPORATION OF DELAWARE.

COOLING DEVICE FOR COMPRESSORS AND CONDENSERS.

Application filed December 2, 1925. Serial No. 72,725.

This invention relates primarily to a cooling device and more particularly to a cooling device associated with a refrigerating unit in which a motor-operated fan is mounted upon a base section containing a condenser, between the pipes of which air is drawn by means of the fan to not only cool the condenser but to direct currents of air against the compressor of the refrigerating unit to cool the same.

It is an object of this invention to provide a simplified form of cooling device for both the compressor and the radiator type condenser of a refrigerator unit.

It is also an object of this invention to provide a refrigerating unit with a cooling device adapted to be mounted between the compressor and driving motor of a refrigerating unit to draw air upwardly through the condenser-containing base of the unit to cause the air to first cool the condenser and then be directed against the compressor to cool the same.

It is an important object of this invention to provide a refrigerating unit wherein a cooling device operated from the motor of the unit is adapted to act as a means for cooling both the condenser and the compressor by drawing air through the condenser-containing base into a hood for discharge against the compressor.

Other and further important objects of this invention will be apparent from the disclosures in the specification and accompanying drawings.

The invention (in a preferred form) is illustrated in the accompanying drawings and hereinafter more fully described.

On the drawings:

Figure 1 is a side elevation of a refrigerating unit partly broken away and equipped with an improved cooling device embodying the principles of this invention.

Figure 2 is a transverse vertical section taken on line II—II of Figure 1.

As shown on the drawings:

The reference numeral 1 indicates a pedestal or base of a refrigerating unit, said base being supported on legs 2 and open at the bottom to permit air to be drawn upwardly through the base. The top wall of the base is provided with an opening at 3 in substantially the middle portion of the top wall of the base. As illustrated in Fig-

ures 1 and 2 one end portion of the top wall of the base is provided with a longitudinally disposed pocket or trough 4, the inner end of which is open and communicates with the opening 3 in the top wall of the base. Mounted upon the middle portion of the base 1 is a hood or dome 5 having an outlet opening or mouth 6 formed in the front wall thereof. Also mounted upon the top of the base 1 is a driving motor 6', the shaft 7 of which projects into the hood 5. Mounted on the motor shaft 7 within the hood 5 is a fan wheel 8. Rigidly mounted upon the top of the opposite end of the base 1 is a compressor 9 which is positioned adjacent the open end of the hood 5. Mounted within the base 1 is a radiator type condenser 10 which is connected with the compressor 9 by means of a pipe 11. A baffle wall 12 is mounted within the base 1 above the lower end of the inclined condenser 10.

The operation is as follows:

The refrigerating unit is clearly illustrated in Figure 1 and is adapted to be driven by the motor 6', the shaft 7 of which projects through the hood 5 and is connected with the compressor 9 to drive the same. The refrigerant from the compressor is adapted to be discharged from the compressor 9 through the pipe 11 leading to the radiator type condenser 10 within the base 1. The refrigerant is permitted to flow through the pipes of the condenser 10 to be cooled and condensed before being returned to the compressor.

As illustrated in Figure 1 the fan 8 is mounted on the motor shaft 7 between the motor and the compressor and when operated by the motor shaft 7 acts to draw air upwardly through the open bottom of the base 1 to first cool the condenser 10 after which the air is drawn upwardly into the hood 5 and is discharged through the mouth or opening 6 against the compressor 9 to cool the same. The baffle wall or plate 12 within the base 1 acts to direct the flow of air upwardly from the base into the hood 5. It will thus be seen that the fans 8 is adapted to cause air to flow upwardly through the base 1 and through the hood 5 to cause cooling of both the condenser 10 and the compressor 9 by a very simple arrangement.

We are aware that many changes may be made and numerous details of construction

may be varied through a wide range without departing from the principles of this invention, and we therefore do not purpose limiting the patent granted hereon otherwise than necessitated by the prior art.

We claim as our invention:

1. In a refrigerating unit comprising a base open at the bottom and having an opening in the top thereof, a condenser mounted in said base, a hood mounted on said base over the opening in the top thereof, a motor mounted on said base, a compressor on said base connected with said condenser, a shaft connecting the motor with the compressor and projecting through said hood, and a fan on said shaft within said hood adapted to draw air upwardly through the base to cool the condenser and then direct the air against the compressor to cool the same.
2. A refrigerating unit comprising a base, a condenser therein, a motor and a compressor mounted on said base, a hood mounted on said base between the motor and compressor, said hood having an opening in the bottom thereof communicating with the interior of the base, a second opening in the wall thereof adjacent said compressor, a shaft driven by said motor projecting through the hood and connected to drive the compressor, and a fan within said hood mounted on the shaft to be rotated thereby to cause air to be drawn upwardly through the base to cool the condenser and furthermore adapted to direct air drawn into the hood against the compressor to cool the same.
3. A refrigerating unit comprising a hollow base open at the bottom and having an opening in the top thereof, a hood mounted on said base above the top opening, said hood having an opening therein, a condenser mounted in said base, a compressor and a motor mounted on said base on opposite sides of said hood, a shaft projecting through said hood and connecting said motor with said compressor, means for connecting

said compressor with said condenser, and a cooling device mounted in said hood adapted to be operated by said shaft to cause air to be drawn through the base to cool the condenser and discharged through the opening in said hood to cool the compressor.

4. In a refrigerating unit the combination with a base having an opening therein, of a condenser mounted therein, of a hood mounted on said base and registering with said opening, a shaft in said hood, a motor mounted on said base adapted to drive said shaft, and a fan in said hood mounted on said shaft adapted when operating to cause air to be drawn upwardly through the base to cool the condenser.

5. A refrigerating unit comprising a base having an opening therein, a condenser mounted therein, a compressor mounted on said base, a fan on said base above said opening, and a driving means for said compressor adapted to operate the fan to cause cooling of the condenser and said compressor.

6. In a refrigerating unit, a base having an opening in the bottom thereof, a radiator type condenser within said base, a compressor mounted on said base, and means for drawing air through said condenser and directing the air against said compressor for cooling the condenser and compressor.

7. In a refrigerating unit, a supporting base having an open bottom, a condenser within said base enclosed by the walls and top thereof, a compressor mounted on the top of said base, means for drawing air past the condenser and through an opening in the top of the base, and means for directing the air so drawn through the base onto the compressor.

In testimony whereof we have hereunto subscribed our names.

ROBERT L. ALEXANDER.

HARRY H. WATERS.

WILLIAM WISHART.
